WHEEL COVER

George Albert Lyon, 13881 W. Chicago Blvd.,
Detroit 28, Mich.

Filed Aug. 3, 1960, Ser. No. 61,615

Term of patent 14 years

(Cl. D14—30)

I claim:

The ornamental design for a wheel cover, substantially as shown and described.
